FIREARM

Filed May 28, 1931

UNITED STATES PATENT OFFICE

CRAWFORD C. LOOMIS, OF ILION, NEW YORK, ASSIGNOR TO REMINGTON ARMS COMPANY, INC., A CORPORATION OF DELAWARE

FIREARM

Application filed May 28, 1931. Serial No. 540,642.

This invention relates to firearms of the repeating type, and contemplates a firearm of simple, rugged and durable construction, and one which is simply and easily manufactured.

Repeating firearms comprise at least two general types: the bolt action type, in which the breech and cartridge transferring mechanism is actuated by manipulation of a handle connected with a reciprocating breech bolt; and the slide action type, in which the breech mechanism ordinarily comprises a block having a somewhat complex movement, rather than a simple rectilinear reciprocation, and the breech and cartridge transferring mechanism is actuated by reciprocating a forearm arranged below the barrel. The bolt action type has the advantages of simple and rugged construction; and the slide action type, the advantage of more ready and simple manipulation.

The present invention contemplates a breech mechanism of the bolt action type provided with means whereby it may be operated by the reciprocation of a forearm.

With these and other objects in view, the invention consists in the novel constructions, combinations, and arrangements of parts, hereinafter more fully described, and illustrated in the drawing, in which:

Fig. 1 is a fragmentary side elevation of a firearm embodying the present invention.

Fig. 2 is a fragmentary side elevation of the receiver portion of the firearm, the stock being sectioned and a portion of the receiver wall being broken away to show certain interior mechanism.

Fig. 3 is a fragmentary, top plan view of a firearm embodying the present invention, the breech being closed.

Fig. 4 is a top plan view of the receiver and a fragment of the barrel, the breech being open and a part of the wall of the breech cover being broken away.

Fig. 5 is a section on the line 5—5 of Fig. 1.

Fig. 6 is a section on the line 6—6 of Fig. 1.

Fig. 7 is a section on the line 7—7 of Fig. 1.

The firearm comprises a barrel 10 and a receiver 11, which is preferably made of a single piece of folded sheet metal, having an upper substantially cylindrical bolt receiving portion apertured to accommodate bolt operating and locking devices, and to provide an ejection opening; and a lower portion comprising a pair of spaced substantially parallel flanges 12 and 13. Transverse sections of this sheet metal receiver are shown in Figs. 5 and 6, and its construction is more fully described in my co-pending application, Serial No. 540,641, filed of even date herewith. The forward ends of the flanges 12 and 13 are spaced and joined by a block 14, the lower part of which is elongated, as shown in Fig. 2, to receive a magazine tube 15. Said block 14 is likewise apertured to provide a passage from said magazine to said receiver, and comprises a downwardly extending lug 16 adapted to receive a take-down screw 17 by which a stock 18 is secured to the barrel and receiver assembly.

The construction of the bolt is described in detail in my co-pending application, above-identified. Said bolt reciprocates in the receiver, but it does not rotate. An intermediate section of the bolt is surrounded by an operating ring 19 (Figs. 2 and 6) arranged for rotation upon the bolt. The ring 19 is provided with oppositely disposed projections 20 (Fig. 6) and 21 (Fig. 4) which are received in locking apertures in the wall of the receiver 11. The aperture which receives the projection 20 is a simple slot so located as to come opposite the projection 20 when the bolt is in breech closing position. The aperture which receives the projection 21 is the transversely extending portion of an L-slot 211, the longitudinal part of which is traversed by said projection as the bolt is reciprocated. The breech bolt being forward in breech closing position, and being locked by the engagement of lugs 20 and 21 with their co-operating locking surfaces, the opening of the breech requires two movements: first, the rotation of the ring 19 to disengage projections 20 and 21 from their slots in the receiver; and second, the

retraction of the bolt. Both of these movements are effected by means of a circular lug 22, associated with ring 19, and shown as integral with or rigidly secured to the locking projection 21. Said lug 22 enters a cam slot 23 in a reciprocating operating member or receiver cover 24. Member 24 is of generally cylindrical outline, conforming to the contour of the upper part of the receiver, and is arranged to be reciprocated on the receiver by the operation of a forearm 25 connected to operating links or bars 26 and 27 which in turn are connected to the cover. Cover 24 and links 26 and 27 are preferably integral, and formed from a single piece of sheet metal. Fig. 2 shows the breech bolt forward and locked, the lug 22 being in the rear end of the slot 23. With the parts in this position, if the forearm 25, and with it the cover 24, is drawn rearwardly, the lug 22 first travels to the opposite end of the slot 23 and, owing to the inclination of the slot this movement rotates the ring 19 to disengage projections 20 and 21 from the receiver. The parts are shown in this position in Fig. 3, the squared projection or locking lug 21 being in alignment with the longitudinal portion of the receiver slot in which said projection travels. Further rearward movement of cover member 24 will obviously retract the breech bolt, bringing the parts to the position shown in Fig. 4. Upon the forward stroke of the action bar, the movements just described are reversed, the breech bolt being first brought to its forward breech closing position and the ring 19 subsequently rotated to lock the bolt.

The forearm 25 preferably encircles the magazine tube 15 and is arranged for reciprocation with respect to said tube, the mounting devices comprising a bushing 28 which encircles the tube and is threaded to receive screws 29 and 30 arranged in suitable reinforcing plugs 31 and 32 in the sides of the forearm. The bushing 28 is channeled to receive the forward ends of the bars or links 26 and 27 which are apertured to receive the screws 29 and 30; thus, securing the forearm to the links.

A suitable fire control and cartridge transferring mechanism are more fully illustrated and described in my co-pending application, above-identified. For the purpose of the present application, it is sufficient to say that a suitable carrier device in the receiver is adapted to receive a cartridge delivered from the magazine, elevate such cartridge into alignment with the chamber, insert the cartridge in the chamber, and be restored to depressed position in alignment with the magazine, all under the control of the breech bolt or parts associated therewith.

The embodiment of the invention herein described, and illustrated in the drawing, is to be understood as illustrative, rather than

restrictive, the invention being susceptible of embodiment in many other forms, all falling within the scope of the appended claims.

What is claimed is:

1. A firearm comprising a barrel, a sheet metal receiver adapted to house breech mechanism, a sheet metal breech mechanism operating device mounted upon and substantially covering said receiver and adapted for reciprocation but not rotation relative to said receiver, and operating means for said device comprising a fore-end supported beneath said barrel.

2. In a firearm comprising a barrel, a sheet metal receiver adapted to house a breech mechanism, a reciprocating, non-rotating breech mechanism operating device comprising a sheet metal cover extending the length of and substantially surrounding said receiver, operating links extending forward from and integral with said sheet metal cover, and a reciprocating fore-end supported beneath said barrel and secured to said links.

3. A firearm comprising a receiver adapted to house breech mechanism, an operating lug for said breech mechanism projecting from said receiver, a reciprocating, non-rotating housing extending the length of said receiver and comprising a cam slot adapted to receive said lug, and means for reciprocating said housing.

4. In a firearm comprising a breech bolt adapted for reciprocating movement, a locking and operating device for said breech bolt comprising a ring mounted for rotation thereon, locking lugs projecting from said ring, an operating lug associated with said ring, and a manual operating device adapted for reciprocating movement and comprising a cam slot adapted to receive said lug.

5. A firearm comprising a receiver adapted to contain a reciprocating breech bolt, a breech bolt reciprocable therein, breech bolt locking apertures in said receiver, cooperating locking devices associated with said breech bolt and adapted to be rotated into engagement with said locking apertures, an operating lug associated with said breech bolt and locking devices, and means for rotating said locking devices and reciprocating said breech bolt comprising a reciprocating member provided with a cam slot adapted to receive said lug.

6. A firearm comprising a barrel, a reciprocating non-rotating breech bolt, a ring rotatably mounted on said breech bolt, locking lugs projecting from said ring, an operating lug extending from one of said locking lugs, a reciprocating, non-rotating breech cover comprising a cam slot adapted to receive said operating lug, and connections from said cover to a fore-end supported beneath said barrel.

7. A firearm comprising a receiver of sheet metal, a reciprocating, non-rotating breech bolt mounted in said receiver, a ring rotatably mounted on a portion of said 5 breech bolt intermediate its ends, locking lugs projecting from said ring, locking apertures in said sheet metal receiver adapted to receive said lugs, an operating lug associated with one of said locking lugs, a reciprocating, non-rotating sheet metal breech 10 cover extending substantially the length of said receiver and provided with a cam slot adapted to receive said operating lug, and means for reciprocating said breech cover.
